UNITED STATES PATENT OFFICE.

HAROLD H. FEBREY, OF NEWARK, NEW JERSEY, ASSIGNOR TO THE AMERICAN STEEL AND WIRE COMPANY OF NEW JERSEY, OF HOBOKEN, NEW JERSEY, A CORPORATION OF NEW JERSEY.

RAIL-BOND.

1,394,818.

Specification of Letters Patent. Patented Oct. 25, 1921.

Application filed May 28, 1918, Serial No. 237,096. Renewed March 24, 1921. Serial No. 455,323.

To all whom it may concern:

Be it known that I, HAROLD H. FEBREY, a citizen of the United States, and resident of Newark, in the county of Essex and State of New Jersey, have invented certain new and useful Improvements in Rail-Bonds, of which the following is a specification.

My invention relates to the construction of rail bonds used in electrically connecting the abutting ends of track rails, third rails and the like, and while not limited to such type, more particularly relates to the construction of rail bonds of the "tunnel" type in which the flexible conductor of the rail bond is positioned in the recess or tunnel formed between the rail web and opposite face of the adjacent splice bar used in mechanically fastening the adjacent ends of contiguous rails, instead of extending 20 around the splice bar on the exterior thereof.

Heretofore, in so far as I am aware, it has been the practice with rail bonds of the tunnel type, to apply the splice bars to the rail ends after the bond terminals are fastened to the rails, this being made necessary because of the size and shape of the rail bond terminals, they being too large to pass through the tunnel formed between adjacent faces of the rail web and splice bar, 30 when the splice bar is bolted in place.

One object of my invention is to provide a rail bond of the tunnel type, having novel means enabling the bond to be put into place in the tunnel and welded or otherwise fastened to the rails after the splice bars have been applied to the rails.

Another object of the invention is the provision of a rail bond having terminals shaped to fit the angle of the rail at the intersection of the rail web with the head or base of the rail, and arranged to avoid the necessity of making right and left hand terminals.

Another object of this invention is the provision of a rail bond having terminals which extend lengthwise parallel with the length of the flexible rail bond conductor.

A further object of the invention is to provide a rail bond having terminals of novel construction enabling the terminals to be readily attached mechanically to the ends of the rail bond conductors in the field or in the shop.

A further object of my invention is to

provide a rail bond having a flexible conductor with terminals mechanically secured on the ends of the conductor and provided with transverse notches or grooves in one side of the terminal which coact with the web of the track rail to form a recess or pocket to receive metal added to the terminals in attaching the terminals to the rails, and enable the terminals to be simultaneously welded to the rails and to the ends of the rail bond conductor. 55

Still further objects of my invention consist in providing a rail bond having the novel constructions, arrangements and combination of parts, shown in the drawings, and to be described in detail hereinafter and particularly pointed out in the appended claims. 60

Referring now to the drawings, forming part of this specification, Figure 1 is a side elevation showing a rail bond of the tunnel type, constructed and arranged and applied for use in connecting the abutting ends of two rails, in accordance with my invention. 75

Fig. 2 is a sectional end elevation of the apparatus shown in Fig. 1, the section being taken on the line II—II of Fig. 1.

Fig. 3 is a sectional elevation, similar to that of Fig. 2, the section being taken on the line III—III of Fig. 1.

Fig. 4 is a sectional elevation, like that of Figs. 2 and 3, the section being taken on the line IV—IV of Fig. 1. 80

Fig. 5 is a plan, on a larger scale, showing details in the construction of the rail bond terminals, forming a novel feature of my invention. 85

Fig. 6 is a side elevation of the parts of the apparatus shown in Fig. 5.

Fig. 7 is a sectional end elevation, taken on the line VII—VII of Fig. 6. 90

Fig. 8 is an end elevation of one of the terminals looking at the face most distant from the cable.

In the accompanying drawings, the numerals 2 and 3 designate the abutting ends of two track rails or third rails which are mechanically connected by means of splice bars 4—4, the splice bars being fastened in place by track bolts 5 which extend through registering holes in the splice bars 4—4 and 100 the web of the track rails 2, 3. The shape of the opposite faces of the rail and splice bars is such as to form an opening or tunnel. 105

7 through which the flexible conductor 8 extends when the bond is being applied to the abutting rail ends.

Each end of the conductor 8 is provided with a terminal 9, and the terminals which preferably are cheaply made of a malleable ferrous metal, although any suitable metal or alloy may be employed, are arranged to extend lengthwise parallel with the length of the conductor 8. (See Figs. 1, 5, and 6.)

The terminals 9, which are of substantially triangle cross-section, have opposite side surfaces 10, 10 forming an included angle of less than 90 degrees, the other side or base of the triangle extending substantially at right angles to the medial line XX of Fig. 7, and in this way the necessity of making right and left hand terminals is avoided. It is obvious, however, that the cross-section of the terminals may be varied to suit conditions, as found necessary or desirable.

The terminals 9 have a transverse notch 12 in the upper side thereof forming a pocket for the metal used in welding or otherwise fastening the rail bonds to the rails, this pocket having oppositely inclined sloping surfaces 13 and 14.

The terminals also have opposite lugs 15, 15 on the upper side thereof, these lugs forming an open sided slot or groove in which the conductor ends are secured in mechanically fastening the terminals on the conductor 8. The so-formed slot extends lengthwise parallel to the length of the terminals and preferably is made tapering, with the large end of the slot adjacent to the transverse notch 12. (See Figs. 5 and 6.) The lugs 15 are readily bent down into tight holding engagement with the ends of the conductor, either by power means or with a hammer.

It will be noted that the sloping surface 13 of the pocket 12 causes a larger end surface of the conductor ends to be exposed to contact with the metal 16 added in welding the bonds to the rails.

In the construction of rail bonds made in accordance with my invention, the terminals 9 will be formed as shown, and preferably one of the terminals will be mechanically fastened to the end of the conductor 8 in the shop by bending over the lugs 15 into close holding engagement with the end of the conductor.

In applying a rail bond to the rails, the end of the conductor 8 not having a terminal thereon, will be threaded through the tunnel 7, this being made possible by the omission of the terminal on one end of the conductor. A second terminal 9 is then fastened on the projecting end of the conductor 8, this terminal being readily applied by hammering over the lugs into holding engagement with the conductor, after the

conductor is inserted in the tunnel 7. The terminals being symmetrical about the medial line XX of Fig. 7, the making of right and left hand terminals is made unnecessary.

The surface of terminals 9 and the rails 2 and 3 at the point of application of the terminals, will be cleaned to remove all scale or oxid, preparatory to applying the rail bonds.

After the second one of the terminals 9 is secured on the end of the bond conductor, the terminals are placed in position at the juncture of the rail web with the upper surface of one flange of the rail base. When in this position the transverse groove 12 in one face of the terminals coacts with the vertical face of the rail web to form a pocket or recess, adapted to receive the fused metal or alloy, with which the pocket is filled in fastening the terminals to the rails. 85

The terminals 9 are then heated, electrically, or by means of a blow-torch, or in any other approved manner, and at the same time the ends of the conductor 8 and adjacent surfaces of the rail will become highly 90 heated. A suitable flux will be used to prevent oxidation of the surfaces during the heating operations. A metal or alloy pencil is then introduced into the zone of heating and is thereby fused, and molten metal is 95 added until the pocket formed by the groove 12 in the terminals and opposite surface of the rail web is filled. More metal may be added on top of the terminals until it is built-up as shown in Figs. 1, 2, and 3, and 100 the rail bond is thereby welded to the rail ends. At the same time the added metal 16 welds to the exposed end surface of the conductors 8 so that in applying the bonds to the rails, the metal 16 added in welding is 105 welded to the rails 2, 3, the terminals 9, and also to the ends of the rail bond conductor 8.

The advantages of my invention will be apparent to those skilled in the art. The rail bond is of simple construction and is 110 easily and cheaply made, and is readily fastened to the rails, and the necessity of applying the rail bonds to the rails before fastening the splice bars in place is rendered unnecessary.

An important feature of my improved tunnel type of bonds is that one or both of the terminals may be carried separately and be mechanically attached to the end or ends of the conductor in such a way as to expose 120 the end portion of the conductor so that this and the terminal can be welded to the rail at one operation.

Various modifications in the construction and arrangement of the parts may be made 125 without departing from my invention as defined in the appended claims.

For example, the terminals may be applied to other points of the head, web or base of the rail and may be suitably modified 130

in shape to fit them to such points; and they may be applied to the rail either by the gas flame method described or by any other known or suitable method.

5 I claim:—

1. A rail bond adapted for welding to the side surfaces of the rails and comprising a flexible conductor, having terminals on the ends thereof extending lengthwise 10 parallel with the length of the conductor, said terminals having opposite lugs on one side arranged to bend into holding engagement with the conductor ends, to thereby mechanically connect the terminals to said 15 conductor, and having a transverse notch in one side forming a metal receiving pocket arranged to permit the rail, the conductor and the terminals to be united by the fused metal used in welding the rail bond to the 20 rail.

2. A rail bond adapted for welding to the side surfaces of the rails and comprising a flexible conductor, having terminals on the ends thereof extending lengthwise parallel 25 with the length of the conductor, said terminals having opposite lugs on one side arranged to bend into holding engagement with the conductor ends, to thereby mechanically connect the terminals to said conductor, and having a transverse notch in the side having the lugs forming a metal receiving pocket arranged to permit the rail, 30 the conductor and the terminals to be united by the fused metal used in welding the rail bond to the rail.

3. A rail bond adapted for welding to the side surfaces of the rails and comprising a conductor and terminals on the ends thereof, said terminals extending lengthwise 40 parallel with the length of said conductor, and having a transverse notch in one side forming a metal receiving pocket

arranged to permit the rail, the conductor and the terminals to be united by the fused metal used in welding the rail bond to the 45 rail.

4. A rail bond adapted for welding to the side surfaces of the rails and comprising a conductor and terminals on the ends thereof, said terminals extending lengthwise 50 parallel with the length of the conductor, and having two angular side surfaces arranged to contact with the surfaces of the rails in welding the rail bond to the rail, a portion of said terminals being cut away, 55 forming a pocket adapted to retain molten metal used in welding the bonds to the rails.

5. A rail bond adapted for welding to the side surfaces of the rails and comprising a conductor and terminals on the ends 60 thereof, said terminals extending lengthwise parallel with the length of the conductor, and having two angular side surfaces arranged to contact with the surfaces of the rails in welding the rail bond to the rail, 65 and the third side of said terminals having a transverse notch coacting with vertical surfaces of the rails to form pockets, said pockets being adapted to retain molten metal used in welding the rail bonds to the 70 rails.

6. A rail bond adapted for welding to the side surfaces of the rails and including a conductor and a terminal extending lengthwise parallel with the length of said conductor and having a slot at one end for receiving the end of the conductor, said slot being flared toward its inner end and the conductor being correspondingly expanded to fill said slot. 75

In testimony whereof I have hereunto set my hand. 80

HAROLD H. FEBREY.
